[57] CLAIM

The ornamental design for an in-line filter for laboratory use, as shown and described.

DESCRIPTION

FIG. 1 is a perspective view of an in-line filter for laboratory use showing my new design;

FIG. 2 is a top plan view of the filter of FIG. 1;

FIG. 3 is a side elevational view of the filter of FIG. 1; the broken lines are shown for illustrative purpose only;

FIG. 4 is a bottom plan view of the filter of FIG. 2;

FIG. 5 is a cross-sectional view taken along line 5—5 of FIG. 4.

FIG. 1.

FIG. 2.

FIG. 3.

FIG. 4.

FIG. 5.
